(57) **CLAIM**

The ornamental design for a tire shoulder tread, as shown and described.

DESCRIPTION

FIG. 1 is a perspective view of a tire shoulder tread showing the new design, it being understood that the shoulder tread pattern repeats circumferentially throughout the shoulder of the tire, the opposite side perspective being identical thereto; FIG. 2 is a front elevation view thereof; and,

FIG. 3 is a side elevation view of the right side thereof, the left side elevation being identical thereto.

In the drawings, the heel or crown of the tire is shown with a “generic” pattern for the purpose of showing the environmental structure of a tire and forms no part of the claimed design. In the drawings, the broken line disclosure of the tire sidewall and inner bead depicts environmental structure and forms no part of the claimed design.
